SOUND-TRANSLATING MACHINE

Barton A. Proctor, Larchmont, N. Y., assignor to
 B. A. Proctor Company, Inc., New York, N. Y.,
 a corporation of New York

Application May 5, 1942, Serial No. 441,765

8 Claims. (Cl. 274—9)

This invention relates to sound translating machines of the general class disclosed in Serial No. 218,082, filed July 8, 1938, for Sound recording and reproducing; Serial No. 281,811, filed June 29, 1939, for Sound recording and reproducing, and Serial No. 417,072, filed October 30, 1941, for Sound recording and reproducing devices.

These machines are primarily designed for dictation purposes, although they are adapted also for other uses.

The machines are adapted to record upon, and to reproduce from, a thin, freely flexible, distortable, disc record of plastic material. When a relatively thin cellulose acetate record, say one having a thickness of substantially .005 inch is employed with a relatively heavy recording stylus pressure, the formation of the spiral sound track in one face of the record presses through a corresponding spiral ridge on the back face of the record. When a somewhat thicker cellulose acetate record is employed, say a record having a thickness of substantially .0075 inch with a relatively light recording stylus pressure, the record is not through-deformed, and distinct recordings may be made on opposite faces of the record.

In either case, however, the action of the recording stylus produces a certain distortion of the record causing the record to assume a wavy, irregular, curled or dished shape. This distorted condition of the record gives rise to certain problems which are solved broadly in the machines of the prior applications referred to, and to certain more specific problems which it is the purpose and object of the present invention to overcome.

The distortion of the record at recording makes it impractical to undertake to record upon or to reproduce from the record by mounting the record upon a rotatable turntable. For this reason, among others, each of the prior machines is made to include a center spindle for supporting the record at the center and for defining an axis of rotation for the record, a platen wheel running in engagement with the lower face of the record, a stylus engageable with the upper face of the record in opposition to the platen wheel, opposed feed wheels for directly engaging and driving the record, and means for relatively shifting the center spindle, on the one hand, and the stylus and platen wheel on the other, as the sound translating progresses, together with a stationary arched support for the record about which the record is partially wrapped, and upon

which the record is progressively flexed as it rotates. All of the foregoing features are retained in the present machine.

It has been found, however, that the employment of a smooth-faced, arched support of uniform cross-section has certain drawbacks and disadvantages. The arched support is designed to serve as a record brake, for bringing the record quickly to rest when the drive is interrupted. The support of uniform cross-section, however, is found to exert considerably more of a frictional braking effect than is actually necessary for practical purposes, and the excessive friction is found to produce objectionable wear upon portions of the arched support, making frequent replacement necessary. The arched support of uniform cross-section, moreover, has been found to have a tendency, through its action on bulged portions of the distorted record, to lift the center of the record relative to the center spindle.

When the recording stylus presses the sound track into the thin plastic cellulose acetate sheet, it causes the cellulose acetate sheet to stretch. As the recording progresses from the center outward, the record area is expanded. The record material in the surrounding, unrecorded area, however, remains in normal condition. The expanded material, therefore, develops into a saucer-like shape. The material is so thin that the center of the disc is caused to bulge upward when the sides of the disc are bent downward into general conformity with the arched support. When the slightly thicker record for double faced recording is employed, the dishing or bulging is still present, although less marked than in the case of the thinner, single faced record. The improved construction of the arched support to be described is suitable, however, for coacting properly with either type of record.

In accordance with a practical and advantageous feature of the present invention, the difficulties referred to are overcome by making the arched support of uniform width but of varying height, with the top of the arched support of greatest height midway of the length of the support and of progressively diminishing height from the middle toward the ends. All portions of the arched support lie below the spindle supported center of the record.

In accordance with a further feature of the invention the arched support is provided with a multiplicity of spaced ribs or other projections at its upper or outer face for preventing contact of the under surface of the record with the major portion of the outer face of the support. This

tends to reduce friction and wear, particularly by reducing adhesion effects resulting from static electricity and suction.

In the prior machines referred to, stationary guide members were provided at the front and rear of the machine to extend over the sides and shoulders of the arched support, the guide members being curved in general conformity with the curvature of the support and spaced substantially from the support. Since both guide members were stationary, it was necessary first to insert opposite margins of the records beneath the front and rear guides while holding the center of the record arched over the center spindle, and then to press the center of the record down onto the center spindle.

In accordance with the present invention the guide member at the front of the machine is hingedly mounted upon the machine frame so that it can be swung away from the arched support to make the arched support fully accessible at the front of the machine. With this arrangement the hinged guide member may be swung forward out of the way, the record may be thrust around from the front over the center spindle and beneath the rear guide member, and the hinged guide member may then be swung back to operative position to press and push the marginal portion of the record at the front of the machine down into the space between the arched support and the hinged guide member in the position of the latter normally occupied during operation of the machine.

Other objects and advantages will hereinafter appear.

In the drawings forming part of this specification

Fig. 1 is a view of the machine in front elevation, the record being shown in place but sectioned so as not to affect the illustration of the machine parts;

Fig. 2 is a fragmentary, longitudinal sectional view through a portion of the arched support, showing the surface configuration thereof;

Fig. 3 is an idealized or suggestive sectional view of the record showing in a general way the shape which the record tends to assume as the recording proceeds, the deformation of the record being considerably exaggerated, and shown as much more regular than it is in actual practice;

Fig. 4 is an end view in elevation of the machine of Fig. 1 looking at the machine from the left-hand end; and

Fig. 5 is a fragmentary, detail view showing a modified form of the arched support.

The machine is generally the same in construction and principle of operation as the machine of Serial No. 281,811 to which reference may be had for a more complete disclosure of details of the operating mechanism.

Briefly, the machine comprises a frame or housing 1 in which is mounted a record carriage (not shown). A center spindle 2, supported on the carriage, extends upward and constitutes a means for supporting the center of a record 3 and for defining an axis of rotation for the record. The center spindle is rotated by the record itself, and serves through its rotation to drive a feed screw (not shown) by means of which the center spindle is caused to travel from right to left, Fig. 1, as the recording or reproducing proceeds.

The record is driven by upper and lower feed wheels 4 and 5 which directly engage opposite faces of the record. Recording and reproducing

styli 6 and 7 are adapted to be brought alternatively into effective, record engaging position opposite a freely rotatable, record engaging platen wheel 8.

5 Operation of a control handle 9 to its extreme right-hand position against a stop 10 as shown in Fig. 1 makes the recording stylus 6 as well as the feed wheels 4 and 5 effective. When the control handle 9 is moved to an upright position, 10 both styli are out of engagement with the record, and the feed wheel 4 is withdrawn from engagement with the record to interrupt the record drive. When the control handle 9 is moved to its extreme left-hand position against a stop 11, the 15 reproducing stylus is made effective and the feed rollers 4 and 5 are also made effective.

An arched, stationary record support 12, desirably of sheet metal, is fixedly mounted on the machine frame 1. The lower side walls of the 20 support 12 extend vertically but merge through smoothly rounded shoulder portions with a curved top portion of the support. The top of the support is formed with a slot 13 through which the center spindle 2 extends, and along 25 which the center spindle travels.

At the back of the machine, the frame includes a stationary guide member 14 which extends over the rear shoulder of the support 12 in general conformity with the curvature thereof. The 30 space between the guide member 14 and the support 12 is quite substantial, however, so that there is no cramping or binding of the record in the space between the support and the guide member.

35 A similar guide member 15 is provided at the front of the machine, but in this instance the guide member is mounted upon the frame 1 through the medium of a piano hinge 16. The guide member 15 may be swung forward to the dot and dash line position marked 15a in Fig. 4, when it is desired to place a record in the machine or to remove a record from the machine. When the guide member is thus swung forward, the record may be thrust from the front over the center spindle 2 and into the space between the support 12 and the guide 14. It may then be impaled upon the center spindle and the forward portion of the record may be pressed with the fingers of one hand toward or against the support 12 while the guide member 15 is swung rearward to the full line position illustrated in Fig. 4. An abutment 17 affixed to the arched support 12 limits approach of the guide 15 toward the support, so that the normal guide space at the front of the machine is the same as that at the rear. In the operative or full line position of the guide 15 the guide is urged by gravity toward the support 12. When the guide is swung forward, however, it crosses dead center and is urged by gravity away from the guide 12. Suitable friction means may desirably be provided for preventing vibration of the guide 15. The friction may be provided in the hinge 16. The hinge pin may, for example, be of large enough diameter to expand and thereby stress the curled fingers of the hinge leaves by which it is embraced, so that each finger is caused resiliently to grip the hinge pin.

As will be readily seen from an examination of Figs. 1 and 4, the arched support is of uniform 70 width but of varying height. The support is of greatest height midway of its length, and is of progressively diminishing height from the middle toward the ends. Even the highest portion, however, is below the level at which the center of the record is supported by the center spindle. Be-

cause of this construction the total frictional pressure of the record against the support 12 is greatly reduced so that excessive and unnecessary friction is eliminated. This reduces rubbing or scraping noise in the operation of the machine, reduces wear upon the arched support, and greatly reduces the likelihood of the record pressing against the top of the support in such manner as to lift the center of the record relative to the center spindle. When a record is put in place it is held loosely wrapped part way around the arched support. When thus bent and then rotated it develops the saucer shape previously referred to. This is true whether the recorded face be placed downward or upward, and whether one face or both faces are recorded upon. The downward sloping of the top of the arched support from the middle toward the ends is a very effective means of overcoming the adverse effects of this saucer shape of the record.

If a recorded record is placed upon the machine for reproducing, the reproducing, of course, starts in the center. If the arched support were perfectly flat along the top, and in alignment with the upper surface of the record supporting flange of the center spindle, difficulty would be experienced in keeping the center section securely locked to the spindle. There would be a tendency for the center section to rise, because the edges of the record would press against the top of the arched support and tend to lift the center of the record. In the thin, single faced record this would cause a wrinkling of the material over a large area of the center portion. In some cases this wrinkling would be sufficient to cause the reproducer stylus to jump a groove. As the record carriage moves upwardly or toward the left, the edge of the record slides over the end of the machine, and as the record approaches the limit of its travel, this free extension dips slightly and relieves the tendency to wrinkle. The effect of the hump at the middle of the arched support, therefore, is to relieve this pressure until sufficient area of the disc is beyond the edge of the machine to avoid the development of any lifting pressure against the margin of the record.

The arched support 12 is not formed with a plane or even surface, but is formed with a series of spaced parallel ribs 18 which project outward from the general upper and outer contour surface of the support. The record is thus caused to have contact with the ribs, but to be spaced generally from the intervening areas of the support 12. This avoids the development of any suction effect between the record and support, and serves to reduce the friction effect.

In Fig. 5 the arched support 12a is shown as provided with a series of projecting elements or knobs 19 in place of the ribs 18. These projecting elements serve the same function as the ribs 18. In all other respects the arched support 12a is the same as the arched support 12 of Figs. 1 to 4, inclusive, and is adapted to be used in place of the latter.

I have described what I believe to be the best embodiments of my invention. I do not wish, however, to be confined to the embodiments shown, but what I desire to cover by Letters Patent is set forth in the appended claims.

I claim:

1. The improvement in a sound translating machine which includes means for supporting a thin, distortable, freely flexible disc record at the center thereof and defining an axis of rotation therefor, a platen wheel running in engage-

ment with the lower face of the record, a stylus engageable with the upper face of the record in opposition to the platen wheel, means for rotating the record, and means for relatively shifting the axis defining means on the one hand and the stylus and platen wheel on the other as the sound translating progresses, and a stationary arched support for the record characterized by the fact that it is highest midway of its length and has its top sloped downward toward the ends.

2. The improvement in a sound translating machine which includes means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, and means for relatively shifting the axis defining means on the one hand and the stylus and platen wheel on the other as the sound translating progresses, and a stationary arched support for the record characterized by the fact that it is of uniform width but of varying height and has its top of greatest height midway of its length and of progressively diminishing height from the middle toward the ends.

3. The improvement in a sound translating machine which includes means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, and means for relatively shifting the axis defining means on the one hand and the stylus and platen wheel on the other as the sound translating progresses, and a stationary arched support for the record characterized by the fact that it is formed with a multiplicity of spaced raised elements which project beyond the general contour of its upper or outer face for contact with the record.

4. The improvement in a sound translating machine which includes means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, and means for relatively shifting the axis defining means on the one hand and the stylus and platen wheel on the other as the sound translating progresses, and a stationary arched support for the record characterized by the fact that it is formed with a multiplicity of spaced parallel ridges on its upper or outer face for contact with the record.

5. The improvement in a sound translating machine which includes means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, and means for relatively shifting the axis defining means on the one hand and the stylus and platen wheel on the other as the sound translating progresses, a frame, a stationary arched support for the record, guide members extending over the sides and shoulders of the

stationary support at the front and back, said guide members being curved in general conformity with the curvature of the support and spaced substantially from the support, and means for hingedly supporting the front guide member from the frame so that the front of the support can be made fully accessible.

6. The improvement in a sound translating machine which includes means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, and means for relatively shifting the axis defining means on the one hand and the stylus and platen wheel on the other as the sound translating progresses, a frame, a stationary arched support for the record, guide members extending over the sides and shoulders of the stationary support at the front and back, said guide members being curved in general conformity with the curvature of the support and spaced substantially from the support, and means for hingedly supporting the front guide member from the frame so that the front of the support can be made fully accessible, and an abutment means for limiting approach of the hingedly mounted guide member toward the support.

7. A sound translating machine comprising, in combination, means for supporting a thin, distortable, freely flexible disc record at the center thereof and defining an axis of rotation therefor, a platen wheel running in engagement with the

lower face of the record, a stylus engageable with the upper face of the record in opposition to the platen wheel, means for rotating the record, means for relatively shifting the axis defining means on the one hand and the stylus and platen wheel on the other as the sound translating progresses, and a stationary arched support for the record, said support being of uniform width but of varying height and having its top of greatest height midway of its length and of progressively diminishing height from the middle toward the ends.

8. A sound translating machine comprising, in combination, means for supporting a thin, distortable, freely flexible disc record at the center thereof and defining an axis of rotation therefor, a platen wheel running in engagement with the lower face of the record, a stylus engageable with the upper face of the record in opposition to the platen wheel, means for rotating the record, means for relatively shifting the axis defining means on the one hand and the stylus and platen wheel on the other as the sound translating progresses, a stationary arched support for the record, guide members extending over the sides and shoulders of the stationary support at the front and back, said guide members being curved in general conformity with the curvature of the support and spaced substantially from the support, a frame, and means for hingedly supporting the front guide member from the frame so that the front of the support can be made fully accessible.

BARTON A. PROCTOR.
